UNITED STATES PATENT OFFICE.

FRANK W. SMITH, OF KANSAS CITY, MISSOURI, ASSIGNOR, BY MESNE ASSIGNMENTS, TO UNIT MOTOR COMPANY, OF KANSAS CITY, MISSOURI, ORGANIZED UNDER A DECLARATION OF TRUST.

INTERNAL-COMBUSTION MULTIMOTOR.

1,423,365.

Specification of Letters Patent. Patented July 18, 1922.

Application filed July 2, 1919. Serial No. 308,168.

To all whom it may concern:

Be it known that I, FRANK W. SMITH, a citizen of the United States, residing at Kansas City, in the county of Jackson and State of Missouri, have invented certain new and useful Improvements in Internal-Combustion Multimotors, of which the following is a specification.

This invention relates to internal combustion motors and has for its object to produce an efficient and economical multi-motor of small size and compact and light construction suitable for the heavy and strenuous duty required by aeronautical service and adaptable for marine and automobile services and in power plants of all kinds.

A further object is to produce a multi-motor composed of interchangeable units in any desired number and arrangement. Another object is to produce a multi-motor having a mounting adjustable, rotatably around the crank shaft to permit the motor to be fitted to the "job" as distinguished from the conventional motors to which the "job" must be adapted. Another object is to produce a multi-motor having a jointless crank case unit to give maximum security against leakage of pressure and oil, and a further object is to produce crank case units and cylinder bodies in a single casting to further insure against escape of compression and conserve the use of lubricating oil.

A still further object is to produce a multi-motor in which deposits of carbon incident to combustion, are practically avoided; in which each charge of gas while cool, is brought into contact with the piston over a wide area, to cool the same; and in which water, air and liquid fuel are utilized in cooling the cylinder and rendering the operation of the motor more efficient. A still further object is to produce a multi-motor in which the fly wheel can be located at one end of the crank shaft or at an intermediate point between units thereof, accordingly as the "job" makes such assemblage desirable or necessary.

With these and other objects in view as hereinafter appear, the invention consists in certain novel and useful features of con-

struction and combinations of parts as hereinafter described and claimed; and in order that it may be fully understood, reference is to be had to the accompanying drawings, 55 in which:

Figure 1, is a view of a two cylinder motor embodying the invention, one of the motors being shown in elevation and the other in central vertical section.

Figure 2, is a section on the line II—II of Figure 1.

Figure 3, is a central vertical section taken on the line III—III of Figure 1.

Figure 4, is a view showing three units, 65 one in top plan and the other two in horizontal section respectively just above and centrally through the crank case.

Figure 5, is a fragmental side elevation of a unit with the crank shaft omitted to 70 show internal construction of the crank case.

Figure 6, is a perspective view of one of the bushings of the crank case.

Figure 7, is a perspective view on a reduced scale of a crank unit and a wrench 75 for use in detaching the crank shaft members from the crank.

Referring to the drawings in detail and to a single unit of the motor, as the units 80 are of identical construction, the crank case has a narrow central portion 1, for the accommodation of the crank of the motor shaft, provided at diametrically opposite points with elongated vertical openings 2, 85 either of which openings is adapted to be closed by a removable plate 3, which at its inner side conforms to the curvature and constitutes an unbroken portion of the wall portion 1. In the preferred construction, 90 as shown, the portion 1 is provided with aligned outwardly projecting concentric neck portions or flanges 4 and 5 spaced apart to form circular pockets 6 for holding lubricating oil, and braced by radial partitions 7. 95

The upper halves of the inner ends of flanges 5 are formed with U-shaped recesses 8, to permit of the insertion of the crank from the top of the cylinder as hereinafter explained, and fitted in said flanges are 100 bronze bushings 9, having lower semi-cylindrical enlargements 10 fitting in recesses 8,

to receive the hubs of the crank. The outer or cylindrical portions of said bushings contain hard-metal bearing sleeves 11 for quick replacement when necessary, at small cost. 5 The outer end of the inner necks or flanges 4 are provided with outwardly projecting bolting flanges 12 for the connection of units and for other purposes hereinafter explained, and with internal grooves 13 where- 10 in are fitted felt rings 14 for a purpose which hereinafter appears.

The crank is made in a single piece and comprises two arms 15 connected by the crank pin 16, preferably tubular, and said 15 arms are tapered at their outer sides and ends at 17 to provide for clearance in the rotation of the crank within the narrow central portion 1. The crank arms are provided with outwardly projecting hub portions 18 fitting in and bearing a journaled relation to the enlarged portions of the bronze bearing rings 9, and said hub portions are keyed at 19 onto tubular shaft members 20 extending through the hardened 25 sleeves 11, and provided outward thereof with circular heads or flanges 21 formed with channels 22 in their inner faces to permit of the use of bronze bushings and sleeves 11 of the greatest possible length. The peripheral surfaces of heads 21 are contacted by the felt rings 14 for the conservation of oil and exclusion of dust.

Each shaft member head 21 is provided with a circular series of equi-spaced sockets 23, and pressed within the sockets of one of said heads are tubular coupling pins 24, each pin being internally threaded for the reception of a screw, not shown, whereby they may be individually removed from position without injury to their external surfaces. By turning such a screw in one of said pins it eventually engages the bottom of the socket within which such pin fits, and then acts to push or pull the pin out of the socket. If the motor consists of two units, the other shaft head will likewise be provided with a set of pins 24, one end of each engaging a similar socket in the juxtaposed shaft head of the adjacent unit, it being 40 understood in this connection, that a set of pins engaging two of such heads will preferably be pressed tightly into one as above explained, but will have only a close sliding fit with the other, so that the units may be 45 readily fitted together or separated. The said pins are intended merely as couplings to transmit power from one crank to another crank or to a fly wheel or some other object to be rotated. To secure two units together, 50 the flanges 12 of the abutting crank cases, are secured together by a circular series of bolts 25 in the juxtaposed bolt flanges 12. To center abutting crank cases and insure alinement of their bearings, centering rings 55 25^a, are fitted in the circular spaces between

the shaft member heads and the flanges 12, fitting tightly against the latter and with bare clearance with respect to the former. The use of such rings between abutting units of multi-motors avoids dependence for the proper centering of the units upon the use of the bolts 25, and incidentally facilitates the assembling of the units by simultaneous registration of all of the bolting flange holes.

A motor comprising two or more units, 7 will be provided preferably at one end, with a gear wheel 26 and with a fly wheel 27, the gear wheel being perforated to accommodate the coupling pins 24.

The fly wheel is preferably of sheet metal, 80 and provided with an internal circumferential channel 28 to be weighted by a filling 29 of lead or the like, and said wheel is provided with an inner side 30 to fit against the gear wheel, said side being perforated 85 to accommodate the projecting coupling pins, in order that any object to be driven, within or beyond said fly wheel, may be engaged with said pins, which obviously may be of any suitable length. If the fly-wheel is 90 to be arranged between two units of the motor, pins 24 of sufficient length to extend completely through the fly-wheel and into the sockets of such units at opposite sides of the fly-wheel, will be employed. As 95 such arrangement will be obvious by reference to Figure 1, and involves no difference of construction other than the change in length of the pins 24, it is not thought necessary to illustrate it. To secure the gear 100 wheel and the fly wheel rigidly in place, any approved method may be employed, but preferably, a headed bolt 31 is fitted through them and screwed into the juxtaposed shaft member. This closes the latter against loss 105 of compression, and a plug 32 is employed to close the other shaft member against escape therethrough of compression within the crank case. The plug can be removed by a screw driver after bolt 31 has been removed. The latter has a special function in 110 the dismantling of the crank as hereinafter explained.

At each end of the motor an annular motor-mounting angle ring 33 is secured upon 115 the respective flange 12 of the crank case by means of the set of bolts 25 of such flange, and spot-welded or otherwise rigidly secured to each of said rings is a foot 34 adapted to be fastened by bolts or the like, to a 120 cross piece, not shown, for securement to any suitable support for the motor. By this arrangement it will be apparent that by rotatable adjustment of said angle rings on the ends of the motor, the latter can be secured 125 for operation at any desired angle, that is to say, be set with the cylinders hereinafter referred to, horizontal, vertical or at different positions intermediate of the positions mentioned, the changes of adjustment being 130

limited only by the number of perforations provided in said rings for engagement with the said bolts 25, as will be readily understood. The angle rings at one end of the 5 motor also constitutes a housing for the gear 26.

Bolted or otherwise fastened to the peripheral portion of one of the gear-housing angle rings 33, is a housing 35 for a gear wheel 36 meshing with gear wheel 26, wheel 36 being mounted on a suitably-journalized shaft 37 equipped with a small gear 38 meshing with another small gear 39 secured on a second shaft 40, said gears 38 and 39 constituting a 10 pump for circulating water for cooling purposes. The shaft 37 is adapted for operating other accessories of the engine, such for example, as ignition mechanism, not shown. The small gears are enclosed in a figure-8 15 housing 41, the body of which is cast on the cover side of housing 35, and it is closed at one side by a removable plate or cover side 42, these cover sides giving access to the gears above-mentioned.

20 The cylinder 43 is preferably cast integral with the crank case, and for compactness and lightness of construction the latter is recessed to conform to and form the lower part of the chamber of the cylinder, the crank case being formed at opposite sides with a pair of by-pass ports 44 communicating at their lower ends with the crank case adjacent the center thereof and at their upper end with the chamber of the cylinder at the lower extremity of the piston 45 when the same is in its most advanced position, and in order that the flow of gas from the crank case upwardly through ports 44 shall not be choked by the piston when at the rearmost or inner end of 25 its stroke, the piston is provided with a pair of ports 46 to register with the points of communication between the crank case chamber and the inner ends of the ports 44. The head of the piston is arched as at 47 and provided with a cross port 48 to register with and receive gas from the outer ends of ports 44 when the piston is at the rear or inner end of its stroke, and the said arched portion is provided with a central diametric slot 49 30 for discharging the gas from the cross port into the cylinder preliminary to the compression of such charge.

35 By supplying explosive mixture to the compression chamber through the cross port 48 and the slot 49, the cooling effect of each charge is brought to bear on the head of the cylinder centrally of the front end thereof, this method of supplying the gas conserving the supply by preventing or minimizing the 40 loss of any of it with the exhaust gas. It also effects a better scavenging of dead gases from the cylinder than where introduced at one side of the latter, as customary in two cycle engines.

45 It will also be noted that by forming chan-

nels 50 at opposite sides of the neck forming the slot 49, the cool gas within the crank case and piston comes into contact with the full area of the latter and hence assists in preventing the overheating of the same and 50 the cylinder. The discharge slot 49 is of approximately half the capacity of the port 48 in order that the former shall constitute in effect a nozzle for increasing the velocity of the gas and discharging it as a blast against 55 the spark plug 51 and the dome-shaped end or head of the cylinder, this blast tending to keep the spark plug clean and therefore in the best possible working condition. In the preferred construction the piston and the 60 head of the cylinder are made of aluminum alloy and the former and the interior of the latter are polished and buffed to minimize adhesion of carbon thereto by reducing skin friction and hence facilitating the scavenging 65 operation. The piston is operatively connected by the link 52 to the cross pin 16 of the crank and the side edges of the arms of the latter are beveled as at 53 (see Figure 4), for engagement by a wrench herein- 70 after more particularly referred to, to be utilized in dismounting the shaft members 20 from the hubs of the crank, as it is absolutely essential that said parts shall be separable in an engine in which the crank case 75 is cast in one piece as herein shown.

The cylinder and the head are respectively provided with ribs 55 and 54 for air cooling and stiffening purposes. The rib of the cylinder is preferably of spiral form to 80 accommodate the winding around the cylinder of gasoline and water tubes 56 and 57 respectively, the circulation of water through the latter being solely for the purpose of aiding in keeping the cylinder cool, 85 and the circulation of the former assisting in accomplishing this result. The gasoline as it becomes heated by conduction from the cylinder is made more susceptible to quick and perfect vaporization, the discharge end 90 of said gasoline tube being connected in any approved manner to a carbureter (not shown), for connection to the intake manifold 58. The latter is connected to caps 59 secured over one of the openings 2 of each 95 crank case (see Figure 4), and fitted in each of such openings is a plate 60 provided with a pair of openings 61 having spiders 62 for slidingly supporting the stems 63 of a pair of poppet valves 64 seated to control openings 100 61. The plate is provided with a post 65 having a recess 66 for a coil spring 67 so that the same may rock or rotate slightly, and the ends 68 of such spring are loosely looped around grooved collars 69 fitting 105 slidingly on the valve stems and limited as to outward movement thereon by clamp rings 70 fitted in grooves 71 in said stems. By the use of two valves large capacity is 110 provided for with but small valve movement 115 120 125 130

and hence little strain on the spring, the slight rocking of the spring on the post tending to equalize the opening movements of the valves.

- 5 Each cylinder is provided at right angles to the piston ports 46, with a pair of exhaust ports 72, the front and rear margins of which are curved to give a greater area for the exhaust of dead gases than ports of 70
10 the same width with straight front and rear margins, the curving of said margins also serving to maintain external pressure on the piston rings during part of the time said rings are passing such ports. This minimizes chance of the rings bulging slightly as they pass said ports and thus lengthens their period of service.

- In the preferred construction as already described, the cylinder is cast with the crank 20 case and the crank is adapted to be disposed in place by slipping it through the cylinder. The head of the cylinder is secured in place by a series of tie bolts 73 extending down through the head and the 80
25 spiral rib 55 and through an external flange 74 on the cylinder, nuts 75 engaging the ends of the bolts.

- The piston and other parts of the motor are adapted to be lubricated in a well-known 30 manner, that is by introduction of a small quantity of lubricant with the gasoline, but to insure proper lubrication for the journals of the crank shaft members, perforated tubes 76 extend vertically through the necks 35 4 and 5 of the crank case and the bushings 9, and communicate with the pockets 6 thereof. Fitting in said tubes are wicks 77, and engaging the wicks are spring-pressed pins 78, which tend continuously to crowd the 40 wicks upward through the tubes, and bushings and against the sleeves 11, for effectively lubricating the bearings. In practice the exhaust ports 72 of the cylinder or cylinders will be connected to a manifold, not 45 shown. The drawings show and the description relates to a two-cycle engine, and in the operation of each cylinder, the gas compressed by the movement of the piston toward the crank shaft passes from the ports 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 stroke is completed, when ignition takes place and the piston is driven back until it again uncovers ports 72 and renews communication with ports 44, these operations being repetitions of operations already described, the intake valve of course opening under the suction produced by each outward movement of the piston to replenish the charge of gas in the crank case.

In Figure 7 is illustrated a wrench W, 75 to be dovetailed on an arm 15 of a crank unit to close the opening of the hub of said arm, the crank being adjusted cross wise of the crank case so that the wrench can be slipped into the latter through one of the openings 2 after the covering plate thereof is removed. Proper turning of the bolt 31 which is thus bottomed on the wrench, will force outward the surrounding crank shaft member 20 until the same is disengaged from the key 19 and withdrawn from position. This operation, of course, is performed after the units are separated, and after the fly wheel and gear wheel have been removed if in the way of the particular shaft member to be withdrawn. Substantially the same method is employed to remove the other shaft member. After the shaft members are removed and the heads of the cylinders have also been removed, the pistons and cranks are free to be withdrawn from position. It requires a wrench or other suitable device to effect the removal of the shaft members because such members when assembled are forced in under heavy pressure as accurate fitting is essential with an engine designed for high speed operation.

Either of the openings 2 may serve for the intake valve—in fact they may be used simultaneously, especially if a light fuel is desired for starting and a heavy fuel, such as kerosene, for the regular operation of the motor. The openings 2 are elongated not only to give large intake-valve capacity, but also to give access to the interior of the crank case for connecting and also for disconnecting, if desired, the piston rod and crank. A motor of this type can be equipped with a fly wheel at each end, if desired, without interfering with power transmitting mechanism, and it is obvious that power connections can be made at both ends if desired. It will also be obvious that the units of the motor may be in any desired number and in the same or different radial positions to accommodate particular surroundings or to accomplish a special purpose. For example, the crank case units can be arranged in a circle around aligned coupled shaft units, with their cylinders in different radial planes, and if desired there may be a series of such multi-motors having a common shaft, such as the propeller shaft of an aeroplane. The combined power of all of such motors may be used to drive the pro-

5 peller as the aeroplane leaves the ground or to give maximum speed, and one or more can be cut out of service for conservation of fuel or to be utilized if one or more of the 10 active motors fails to function properly. By this arrangement the side torque encountered in driving one of a pair of propellers located out of the longitudinal center of the aeroplane is avoided, and the machine is relieved of twisting stresses incidental to the use of one of a pair of such propellers.

15 From the above description it will be apparent that I have produced a multi-motor having advantageous features which in many respects are suitable for four-cycle as well as two-cycle purposes, but which, as a combined air, water and fuel cooled two-cycle motor is peculiarly desirable for aviation and other purposes where high speed 20 is necessary.

25 It is obvious that the invention is susceptible of modification in various particulars without departing from the principle of construction involved or the spirit and scope of the appended claims.

I claim:

30 1. In an internal combustion engine, a crank case having a central chamber for the crank and two side chambers flanking the central chamber, for holding lubricant, the inner walls of the side chambers having hollow cylindrical portions axially of said central chamber, the inner ends of said cylindrical portions being enlarged and communicating with said central chamber, bushings fitting in and conforming to said cylindrical portions, and wicks within said side chambers and extending up through the said cylindrical portions and said bushings 40 to conduct lubricant to the interior of the latter.

45 2. In an internal combustion engine, a crank case having a central chamber for the crank and two side chambers flanking said central chamber, the inner walls of said side chambers having hollow cylindrical portions axially of the central chamber, said walls being formed with U-shaped recesses constituting enlargements open at the top, for 50 said cylindrical portions and communicating with said central chamber, bushings in said cylindrical portions, provided with U-shaped recesses occupying said U-shaped recesses, a crank in the central chamber having hubs fitting in said enlargements of said bushings, and shaft extensions secured in said hubs and journaled in the portions of the bushings fitting in said cylindrical portions of said inner wall.

55 3. In an internal combustion engine, a crank case having a central chamber for the crank and two side chambers flanking said central chamber, the inner walls of said side chambers having hollow cylindrical portions axially of the central chamber, said

walls being formed with U-shaped recesses constituting enlargements open at the top, for said cylindrical portions and communicating with said central chamber, bushings in said cylindrical portions, provided with U-shaped recesses occupying said U-shaped recesses, a crank in the central chamber having hubs fitting in said enlargements of said bushings, shaft extensions secured in said hubs and journaled in the portions of the bushings fitting in said cylindrical portions of said inner wall, wicks in said side chambers and extending up through said inner walls and the bushings for conducting lubricant to the bushings, and yielding means pressing the wicks into the bushings.

4. In an internal combustion engine, abutting crank-cases secured together and provided with alined bearings, shaft members 85 journaled in said bearings, cranks secured on the shaft members within the crank-cases, and coupling pins extending parallel with and connecting the shaft members of abutting crank cases.

5. In an internal combustion engine, abutting crank-cases secured together and provided with alined bearings, shaft members journaled in said bearings and provided with end sockets, cranks secured on the shaft 95 members within the crank-cases, and tubular, internally-threaded coupling pins extending parallel with and fitting at their opposite ends in alined sockets of adjacent shaft members.

6. In an internal combustion engine, abutting crank cases secured together and provided with alined bearings, shaft members journaled in said bearings and provided at their outer ends with heads, cranks secured 105 on the inner ends of the crank shaft members of each crank case, and coupling pins engaging adjacent crank shaft heads of abutting crank cases.

7. In an internal combustion engine, abutting crank cases secured together and provided with alined bearings, shaft members journaled in said bearings and provided at their outer ends with heads, cranks secured on the inner ends of the crank shaft 110 members of each crank case, and tubular internally threaded coupling pins socketed at their opposite ends in the adjacent crank shaft heads of abutting crank cases.

8. In an internal combustion engine, a 120 crank case having alined bearings, and an opening at right angles to said bearings, a removable plate covering said opening, internally threaded tubular shaft members journaled in said bearings, a crank keyed on 125 the inner ends of said shaft members, and screws fitting in said shaft members and plugging the same.

9. In an internal combustion engine, a 130 crank case having oppositely alined bearings

and an opening at right angles to said bearings, a removable plate closing said opening, internally threaded tubular shaft members journaled in said bearings, a crank keyed upon the inner ends of said shaft members; the arms of the crank having beveled edges, and screws engaging the threads of said shaft members.

10. In an internal combustion engine, a crank case having alined bearings, crank shaft members journaled in said bearings, a crank secured on the inner ends of said crank shaft members, coupling pins projecting outward from the outer end of said crank shaft members, a gear wheel abutting said crank shaft members and perforated to accommodate said pins, a fly wheel abutting said gear wheel and perforated to accommodate said pins, and means for clamping the fly wheel, gear wheel and said crank shaft members rigidly together.
11. In an internal combustion engine, a crank case having alined bearings, tubular internally threaded crank shaft members journaled in said bearings, a series of cou-

pling pins projecting outward from and paralleling one of said crank shaft members, a crank keyed upon the inner ends of said crank shaft members, a gear wheel having perforations accommodating said pins and fitting against the crank shaft member of the latter, a fly wheel having perforations accommodating said pins, and a headed screw extending through the fly wheel and the gear wheel and engaging the internal threads of the abutting crank shaft member to clamp said wheels firmly to the latter.

12. In an internal combustion engine, abutting crank cases secured together and provided with alined bearings, shaft members journaled in said bearings and provided at their outer ends with heads, cranks secured on the inner ends of the crank shaft members of each crank case, coupling pins engaging adjacent crank shaft heads of abutting crank cases, and a centering ring fitted in abutting crank cases to center the shaft members thereof.

In testimony whereof I affix my signature.
FRANK W. SMITH.
